PRESS FOR CUTTING AND CREEASING SHEET MATERIAL

Albert F. Shields, Forest Hills, N. Y., assignor to S & S Corrugated Paper Machinery Company, Inc., Brooklyn, N. Y., a corporation of New York

Application November 28, 1956, Serial No. 43,977

Term of patent 14 years

(Cl. D63—1)

Figure 1 is a perspective view of a press for cutting and creasing sheet material showing my new design.

Figure 2 is another perspective view of the press showing the surfaces thereof not visible in Figure 1.

The essential features of my design reside in those portions shown in full lines.

I claim:

The ornamental design for a press for cutting and creasing sheet material, as shown and described.
